(57) **CLAIM**

The ornamental design for utensil system, as shown and described.

DESCRIPTION

This application is related to co-pending utility application: Application Ser. No. 11/640,699, filed Dec. 18, 2006, and titled “Utensil System” to Ran LERNER.

FIG. 1 is a front view of a utensil system showing my new design;

FIG. 2 is a front view of a rack thereof shown separately for completeness of illustration;

FIG. 3 is a right-side view thereof, the left-side view being a mirror image thereof shown separately for completeness of illustration;

FIG. 4 is a top view thereof, the bottom view being identical thereto shown separately for completeness of illustration;

FIG. 5 is a perspective view thereof shown separately for completeness of illustration;

FIG. 6 is a perspective view thereof, where the rack is in an alternative position shown separately for completeness of illustration.

FIG. 7 is a front view of a knife of FIG. 1 shown separately for completeness of illustration;

FIG. 8 is a right-side view thereof, the left-side view being a mirror image shown separately for completeness of illustration;

FIG. 9 is a front view of a fork of FIG. 1 shown separately for completeness of illustration;

FIG. 10 is a right-side view thereof, the left-side view being a mirror image shown separately for completeness of illustration;

FIG. 11 is a front view of a spoon of FIG. 1 shown separately for completeness of illustration; and,

FIG. 12 is a right-side view thereof, the left-side view being a mirror image shown separately for completeness of illustration.

Applicant regards his design as the display unit for flatware and each utensil shown in FIGS. 1-12, and all portions of the display unit for flatware and utensil.
